UNITED STATES PATENT OFFICE.

GEORGE H. GLASER, OF CLAREMONT, NEW HAMPSHIRE, ASSIGNOR TO SULLIVAN MACHINERY COMPANY, A CORPORATION OF MASSACHUSETTS.

FEED-CONTROLLING DEVICE.

Application filed February 15, 1919. Serial No. 277,348.

To all whom it may concern:

Be it known that I, GEORGE H. GLASER, a citizen of the United States, residing at Claremont, in the county of Sullivan and State of New Hampshire, have invented certain new and useful Improvements in Feed-Controlling Devices, of which the following is a full, clear, and exact specification.

This invention relates to feed controlling devices, and more especially, though not exclusively, to means for controlling the action of the pressure fluid cylinder and piston of a pressure fluid impact tool, such, for example, as a stoping rock drill.

My invention has for its object to provide an improved feed varying means. It is another object of my invention to provide an improved feed controlling attachment which may be applied to a tool feeding device with a minimum change in the structure of the device. Still another object of my invention is to provide an improved adjustable braking means of rugged construction and composed of a minimum number of parts. These and other objects and advantages will, however, hereinafter more fully appear.

In the accompanying drawings I have shown, for purposes of illustration, several embodiments which my invention may assume in practice.

In these drawings,—

Fig. 1 is a side elevation of a stoping drill provided with my improved braking means.

Fig. 2 is a longitudinal sectional view substantially on the line 2—2 of Fig. 1.

Fig. 3 is a transverse sectional view on line 3—3 of Fig. 2.

Fig. 4 is a transverse sectional view on line 4—4 of Fig. 2.

Fig. 5 is a longitudinal sectional view of a modified form of one end of the stoping drill.

Fig. 6 is a transverse sectional view similar to Fig. 4, showing a modification.

Fig. 7 is a transverse section on the line 7—7 of Fig. 2.

In these illustrative constructions, I have shown a pneumatic hammer 1 having a piston 2 movable therein and adapted in its forward movement to strike the shank end of a drill steel 3 to force the bit end of the latter against the material to be cut. Mounted on the rear end of this cylinder 1 is a cylinder head block 4 which forms the

forward head of an air feed cylinder 5, the latter having mounted therein an air feed piston rod 6 carrying on its inner end an air feed piston 7. The piston 7 is preferably provided in a well known manner with a plurality of cup leathers 8 to make the piston air tight with respect to the cylinder 5. The rear end of the air feed cylinder 5 is partially closed by a bushing 9, the air feed piston passing through an opening formed centrally therein. In stoping drills wherein pressure fluid is admitted to both sides of the air feed piston head, this bushing will constitute the rear cylinder head.

As is common in devices of this type now used commercially, a pneumatic cylinder head plug 10 is carried by the cylinder head block 4, this plug being provided with a collar 11 formed thereon in such a manner that it projects into the air feed cylinder 5 and that a recess 12 is formed between this collar and the forward end of the feed cylinder. A recess 13 is formed in the feed piston 7 in axial alinement with the collar 11 in such a manner that the collar may be received by the recessed piston head when the latter is in its innermost position, and a non-positive locking ring 14 is mounted in this recess 13 to frictionally engage the outer surface of the collar 11 to hold the piston against displacement when it is desired to transport the stoping drill.

In the use of rotator drills, it is essential that a handle, such as is shown at 15, be provided, by means of which the operator may keep the pneumatic hammer from rotating during the drilling operation, and, as is common in devices of this type, this handle is made hollow in order that it may serve as an oil reservoir. A filling cap 16 is provided on the outer end of the handle to permit the filling of the latter with lubricant. A valve 17 is preferably mounted on the opposite side from the handle 15, this valve serving to control the pressure fluid supply from the supply line 18' to both the pneumatic feed cylinder and the pneumatic tool. Since the parts so far described are common to certain types of well known stoping drills, it is thought that a further description of these parts or their operation is unnecessary.

In my improved braking mechanism I preferably use a cylinder 19 slidable on and lengthwise of the feeding cylinder 5, adjust-

able braking mechanism carried on one end of the cylinder 19 and adapted to frictionally engage the feed cylinder 5, and a collar 20 interconnected between the cylinder 19 and the feed piston rod 6. The collar 20 may have a threaded connection with the cylinder 19, or may, if preferred, be brazed thereto. This collar is preferably held tightly against the outer end of the feed piston rod 6 by the feed piston rod point 21 which carries a threaded section 23 threadable into the hollow rod 6. A shoulder 22 is provided adjacent the threaded section to abut against the collar 20 to hold the collar 20 in firm frictional engagement with the piston rod 6. If desired, the point 21 may be provided with flatted portions 24 for the reception of a wrench.

The inner end of the cylinder 19 is preferably split for some distance, as shown at 25, so as to provide two oppositely disposed sections which may be flexed toward or away from each other. The end of each of these sections or halves is formed as a U-shaped retainer 26 in which may be inserted a U-shaped liner 27 carrying a friction band 28. As is clearly shown in Fig. 3, the ends of the friction band are slightly separated so that when the two halves 26 of the end 30 of the cylinder 19 are flexed toward each other, the lining 28 may be caused to grip the cylinder 5 tightly.

In my preferred form, the frictional controlling means preferably consists of a U-shaped split band 29 carrying lugs 30 at both ends, these lugs having on their outer surfaces outwardly inclined cam portions 31 adapted to co-act with cams 33 mounted on a rod 32 passing centrally through the 40 cams and cam lugs. The cams 33 and an operating handle 34 are preferably attached to the rod 32 by pins 35, though it is understood that these members may be attached to the rod by any other well known means.

As is clearly shown in Figs. 2 and 3, when the handle 34 is moved from a position substantially at right angles to the axis of the feed cylinder, the co-acting cam surfaces force the lugs 30 toward each other, moving 50 the two halves 26 on the end of the cylinder 19 and causing the friction lining 28 to engage the cylinder 5, the degree of frictional engagement depending upon the degree of movement of the handle 34.

If desired, the retarding device may consist only of the parts hereinbefore described and may be assembled in the manner shown in Figs. 1, 2, and 6, it being clear that when the pressure fluid is admitted to the feed 60 cylinder 5 to act upon the feed piston 7, a part of the pressure which the pneumatic feeding device exerts upon the pneumatic tool may be neutralized by rotating the handle 34 to cause the brake lining 28 to be forced into frictional engagement with the cylinder 5. As the tool is fed toward the work, the feed piston rod, acting through the collar 20 and the cylinder 19, draws the clamping ring lengthwise of the pneumatic feed cylinder, the construction of the braking device being such that the distance to which the stoping drill may be fed is the same as when the braking device is not attached. It should be noted that with the preferred construction herein disclosed, the 70 braking device may be applied as an attachment to any stoping drill, it only being necessary in applying the braking means to remove the point 21, slide the guiding cylinder 19 on the feeding cylinder 5, and replace 80 the point 21 after inserting it through the hole in the collar 20. Stoping drills commonly used are provided with circular piston rods 6', as shown in Fig. 6, it being unnecessary to provide a hexagonal rod as 85 shown in Figs. 2 and 4, unless it is desired to control the path in which the handle 34 moves.

Stoping drills are used for boring holes in all directions to the horizontal, including 90 vertical holes drilled in the roof of a mine, and stoping drills are often used for boring shafts substantially vertically upward. When so used, the cuttings from the drill bit fall onto the operator and make it difficult for him to follow the work or to watch his controlling handles. For this reason, I preferably mount the controlling handle 34 of the braking mechanism in a predetermined position relative to the handle 18 100 which controls the flow of pressure fluid. As shown, the guiding cylinder 19 may be held against rotative movement relative to the cylinder 5 by substituting for the usual cylindrical piston rod 6' shown in Fig. 6 a 105 hexagonal rod 6 (see Figs. 2 and 4) and a bushing 9 having a mating opening therein to guide the rod 6 and to hold this rod against rotative movement. It is to be understood that the piston rod 6 and the 110 bushing 9 may have any other regular or irregular mated surfaces for holding the rod against angular movement relative to the cylinder 5.

Since the threaded connections between 115 the rod 6 and the point 21, the collar 20 and the cylinder 19, and the bushing 9 and the cylinder 5, are often loosened through the jarring of the machine when the latter is operating, I preferably provide means to 120 hold these pairs of elements against relative angular movement. For this purpose I preferably provide the bushing 9 with a hole 36 and depress a portion of the cylinder 5 into this hole. As stated above, the collar 20 125 may be brazed to the cylinder 19, or, if desired, a hole 38 and a depressed portion 39, similar to the hole 36 and depression 37, may be used to keep the member 20 from rotating relative to the cylinder 19. The 130

collar 20 may be held against rotative movement relative to the piston 6 by the use of one or several dowel pins 40 fitted in recesses formed in the collar and piston rod. If desired, a number of holes may be formed in either the collar or the end of the piston rod, or both, and the dowel pins 40 may be made to fit in any of these pairs of holes and thereby adjust the position of the controlling handle 34 relative to the controlling handle 18. The details of its construction will be evident from a consideration of Fig. 7.

If desired, any other of a number of well known means may be used for holding the collar 20 against rotative movement on the threaded portion 23 of the point 21, such as the means shown in Fig. 5, wherein the pin 21' is driven into the end of the piston rod 6, the collar 20' being held on the point 21' by a nut 42'. The collar 20' is held against rotative movement on the point by a flattening of the opposite sides of the point, as shown at 41, and by providing the collar 20' with a bore rounded on two sides and flattened intermediate these two sides to mate with the rounded and flattened portions on the feed piston rod point 21'.

It will be obvious that due to the polygonal shape of the rod 6 and the additional possibility of adjustment by means of the dowel pin 40 and its several holes, it is possible to arrange the handle 34 relative to the handle 18 and the lever 15 in any desired angular relation. Thereby the operator can adjust the parts so that he can at all times have a most convenient arrangement and can also determine, when the parts cannot be conveniently looked at due to dust, spray, or other conditions, their relative positions. Simply stated, it is possible to adjust the parts so that the handle 18 may trace any desired path relative to the lever 34.

While I have in this application specifically described three embodiments which my invention may assume in practice, it is to be understood that the same are used for illustrative purposes merely and that the invention may be modified to assume various forms without departing from its spirit or the scope of the appended claims.

What I claim as new and desire to secure by Letters Patent is:

1. The combination with work performing means and feeding means therefor including a cylinder and piston, of feed controlling means movable with said piston and cooperating with said cylinder to restrain relative movements of cylinder and piston.

2. The combination with work performing means and feeding means therefor comprising a cylinder member and piston member of feed controlling means operatively connected to one of said members at its end remote from said work performing means

and located adjacent the opposite end of said last mentioned member and cooperating at that point with said other member.

3. The combination with work performing means and feeding means therefor comprising cylinder and piston elements, of feed controlling means operatively connected to one of said elements and located continuously adjacent the same and cooperating at that point with the other of said elements. 70

4. The combination with work performing means and feeding means therefor including a cylinder and piston, one of which is attached to said work performing means, of feed restraining means relative to which 80 said cylinder is movable.

5. The combination with work performing means and feeding means including inner and outer telescoping members, of feed controlling means comprising a feed restraining means attached to said inner member and cooperating with said outer member. 85

6. The combination with work performing means and feeding means including 90 inner and outer telescoping members, of feed controlling means comprising a feed restraining means concentrically arranged with respect to said telescopic members and movable with the inner one and cooperating 95 with the other.

7. The combination with work performing means, and means including a cylinder and piston for feeding said work performing means of feed controlling means comprising 100 a feed restraining means operatively attached to said piston and frictionally engageable with said cylinder.

8. The combination with work performing means and means including a cylinder and piston for feeding said work performing means, of feed controlling means comprising a feed restraining means operatively attached to said piston and frictionally engageable with said cylinder, and means for 110 varying the frictional engagement between the restraining means and the cylinder.

9. The combination with work performing means and means for feeding the work performing means including a member forming 115 a unitary structure with said work performing means and a second member telescopically arranged with respect to said first member, of a frictional feed regulating means bearing a fixed relation to said second mentioned member during relative movement of said members. 120

10. The combination with work performing means and means for feeding said means including a member forming a unitary 125 structure therewith and a second member telescopically arranged with respect to said first member and having an abutment engaging end, of frictional feed regulating means connected to said abutment engaging 130

end of said second mentioned member and located adjacent the opposite end thereof.

11. The combination with work performing means and means for feeding said work performing means including a cylinder, a piston therein and a piston rod, of feed restraining means comprising a member located adjacent said piston and connected to said piston rod at the end thereof remote from said piston.

12. The combination with work performing means and means for feeding said work performing means, of feed regulating means comprising a member movable on said feeding means relatively to said first named means, and means for guiding said regulating means in its movements relative to said first named means.

13. The combination with work performing means and means for feeding said work performing means, of feed regulating means comprising a member movable on said feeding means in any one of a plurality of guided movements relative to said first named means, and means for guiding said regulating means in any one of its movements relative to said first named means.

14. The combination with work performing means and means comprising a cylinder and a piston rod for feeding said work performing means, of feed restraining means comprising a member detachably secured to the piston rod, a member connected thereto and disposed longitudinally of and movable longitudinally relative to said cylinder, a cylinder engaging means carried by said last named member, and means for moving said engaging means to cause said means to engage the cylinder.

15. The combination with work performing means and means comprising a cylinder and a piston rod movable in guided relation relative to said cylinder for feeding said work performing means, of feed re-

straining means comprising a member detachably secured to the piston rod, a member connected thereto and disposed longitudinally of and movable longitudinally relative to said cylinder, a cylinder engaging means carried by said last named member, and means for moving said engaging means into engagement with the cylinder.

16. The combination with a stoping drill having a pneumatic tool, a pneumatic feeding means, a pressure fluid controlling valve, and an operating handle therefor, of a feed varying means mounted on said feeding means and having a controlling handle adapted to maintain a fixed angular relation to said valve handle during the feeding of said tool, and means whereby said angular relation may be changed.

17. The combination with a stoping drill having a pneumatic tool, a pneumatic feeding means, a pressure fluid controlling valve, and an operating handle therefor, of a feed varying means mounted on said feeding means and having a controlling handle adapted to remain in fixed angular position relative to said valve handle during feeding, and a plurality of means for varying said angle.

18. The combination with a stoping drill comprising a pneumatic tool, a pneumatic feeding means therefor comprising a cylinder, a piston, a piston rod, a pressure fluid controlling valve, and an operating handle therefor, of a feed varying means mounted on said feeding means and having a controlling handle adapted to remain in a fixed relative angular position relative to said operating handle during feeding of the tool, and means comprising guiding elements carried by said cylinder and rod for controlling the path of movement thereof.

In testimony whereof I affix my signature.

GEORGE H. GLASER.
